UNITED STATES PATENT OFFICE.

COY R. BOND, OF IDAHO, OHIO.

GATE-LATCH.

1,236,255.

Specification of Letters Patent.

Patented Aug. 7, 1917.

Application filed April 20, 1915. Serial No. 22,683.

To all whom it may concern:

Be it known that I, COY R. BOND, a citizen of the United States, residing at Idaho, in the county of Pike and State of Ohio, have invented new and useful Improvements 5 in Gate-Latches, of which the following is a specification.

This invention relates to improvements in latches and has relation more particularly 10 to that class thereunder known as gate latches.

The primary object of this invention is the provision of a device of this character wherein means are employed for causing an 15 automatic latching of the gate when the latter is swung to a closed position.

A further object of the invention is the provision of a device of this character including a pair of spring pressed members, 20 and means for holding the members in spaced relation, preventing the overlapping of the members and further permitting the latch of the gate to be received therebetween for retaining the gate in closed position.

25 The invention consists in the novel features, details of construction and combination of parts which will hereinafter be more fully set forth, illustrated in the accompanying drawing and pointed out in the appended claim.

In the accompanying drawing:—

Figure 1 is a plan view showing the device attached to a gate post.

Fig. 2 is an enlarged vertical detail section taken on line 2—2 of Fig. 1.

Fig. 3 is an enlarged horizontal section.

Fig. 4 is a detail perspective view of one of the jaws.

Referring more particularly to the accompanying drawing, 5 denotes the keeper which in this instance comprises a casing 6 made of metal and the like material and including a bottom wall 7, oppositely disposed upwardly and inwardly inclined walls 8 and 9 and oppositely disposed spaced side walls 10 and 11. The ends of the casing are detachably secured to the bottom wall 6 by means of fasteners 12 such as screws and the like, whereas the side walls of the casing are 45 detachably secured to the opposite side edges of the end walls by means of screws 13. The opposite ends of the side walls are beveled as at 14, to conform with the inclination of the end walls 7 and 8. The bottom walls 6 of the casing is of a length greater than the length of the side walls of the casing, to

provide the said bottom wall with attaching extensions 15 formed with apertures 16 for the reception of fasteners 17, whereby the keeper may be permanently secured to the 60 fence post A, as illustrated in Fig. 1 of the drawing. The upper longitudinal side edges of the side walls 9 and 10 of the casing 6, are formed at their medial portion with horizontally alined V-shaped recesses 18, the purpose of which will be hereinafter set forth.

Disposed in the casing 6 is a pair of clamping jaws 19 and 20, pivotally connected therein adjacent their lower ends as at 21, at a point to opposite sides of the V-shaped notches 18. The said jaws at a point adjacent their upper or active ends, have formed in their opposed faces V-shaped gripping surfaces 22 and 23, each of such gripping surfaces constituting diverging 75 walls 24 and 25, whereby forming between the jaws, when the jaws are in active position, a substantially diamond-shaped keeper space 26, the said jaws are terminally formed with upwardly and outwardly opposed inclined walls 27, forming the jaws with a flared latch entrance 28. The jaws are retained in closed position at all times through the medium of the flat springs 29 and 30. Each of said springs are looped at their 80 terminal portions to provide a lower eye 31 and an upper eye 32. A pin 33 passes through the side walls 9 and 10 of the casing and through the lower eye 31 of the flat springs, for connecting the springs to 90 and within the casing, at a point in longitudinal alinement with the axis of the jaws, while the opposite or upper ends of the springs have their eye portions 32 seated within a recess 34, the latter being formed 95 in the outer longitudinal edge of each of the jaws. The latter mentioned eye portions of the springs are permanently secured within the recess 34 by means of a pintle 35, said pintle passing through the apertures 100 in the side walls of the recess 34 and thence through the eye 32 of the spring.

Formed integral with the inner face 6 of the bottom wall of the casing 5 is an inverted key-stone shaped spacing block 36, 105 having its upper end formed with a V-shaped notch 37, transversely alining with the notches 18 in the side walls of the casing and disposed flush with the lower extremities of the diverging side walls of the 110 gripping surfaces 22 of the jaws, for a purpose which will also be fully set forth.

Connected with the usual swinging gate B is the metallic latch bar 38, which in this particular instance is formed with a hook-shaped attaching end 39 formed with horizontally aligned apertures 40, for the reception of a rivet 41, said rivet passing through the apertures 40 of the latch bar and through the frame of the gate for permanently connecting the latch bar 38 thereto. The latch bar 38 for the greater portion of its length is formed with a squared portion 42, substantially diamond-shaped in cross section and adapted to engage at the points 43 with the flared entrance opening 28, causing the jaws to open and allow the surfaces 43 and 44 of the latch bar 38, to be seated within the diamond-shaped keeper recess 22, snugly engage with the diverging walls of the gripping surfaces 22 of the jaws and repose in the recesses 18 of the side walls of the casing 9 and 10, and thence engage with the notch 37 of the spacing block 36 and permanently retain the gate in a closed position and prevent the same from being accidentally opened.

From the foregoing description, taken in connection with the accompanying drawing, the advantages of construction and of the method of operation will be readily apparent to those skilled in the art to which the invention relates. While I have described the principles of operation of the device together with the device which I now consider to be the best embodiment thereof, I desire

to have it understood that the device shown 35 is merely illustrative and that such advantages may be made when desired as are within the scope of the claim appended hereto.

What is claimed as new is:—

In a gate latch, the combination with a casing including spaced side walls having notches formed in the edges thereof, a post extending transversely of the casing and formed in the free end thereof with a V- 45 shaped notch alining transversely with the notches of the casing, a pair of spring pressed jaws pivotally mounted within the casing at points to opposite sides of said post and having their confronting faces terminally notched to form therebetween upon the jaws assuming a closed position, a substantially diamond-shaped keeper recess 50 alining transversely with the former and latter mentioned recesses, and a gate latch 55 having a squared portion for engagement with a flared entrance opening of the jaws and fitting within the diamond-shaped keeper recess, the notches of the casing and the notch of the block upon the closed position 60 of said gate.

In testimony whereof I affix my signature in presence of two witnesses.

COY R. BOND.
